[57] **CLAIM**

The ornamental design for a steerable inflatable towable vehicle, as shown and described.

DESCRIPTION

FIG. 1 is a perspective view of the steerable inflatable towable vehicle showing my new design;

FIG. 2 is a top plan view thereof;

FIG. 3 is a left side elevational view thereof, the right side elevational view being identical thereto;

FIG. 4 is a bottom plan view thereof;

FIG. 5 is a front elevational view thereof; and,

FIG. 6 is a rear elevational view thereof.
